UNITED STATES PATENT OFFICE.

GEORGE D. GREENWOOD AND JOHN G. JORY, OF BALTIMORE, MARYLAND.

AUTOMATIC RAILWAY-SIGNAL.

SPECIFICATION forming part of Letters Patent No. 417,022, dated December 10, 1889.

Application filed May 1, 1889. Serial No. 309,229. (No model.)

To all whom it may concern:

Be it known that we, GEORGE D. GREENWOOD and JOHN G. JORY, citizens of the United States, residing at Baltimore, in the 5 State of Maryland, have invented certain new and useful Improvements in Automatic Railway-Signals, of which the following is a specification.

This invention has reference to a block-10 signal system for railways; and it consists in the combination, with semaphores or signal devices, of certain instrumentalities herein-15 after described, whereby the signals are changed or adjusted by the action of compressed air, which is brought into play by a locomotive or train of cars moving along the track.

The invention is illustrated by the accompanying drawings.

20 Figure 1 is a side view of an ordinary signal-post or semaphore. Figs. 2 and 3 are side elevations of the signal devices, and the parts shown in both figures together constitute one block. Fig. 4 is a plan view of the track and 25 certain parts of the signal apparatus. Fig. 5 is a side view showing the power-cylinder and connections and a section of the pump. Fig. 6 is a plan of two power-cylinders on opposite sides of the track and connections. 30 Figs. 7 and 8 show details of the power-cylinders and connected parts. Fig. 9 shows the relative position of two wheel-treadles. Fig. 10 is a section of the operating-cylinder.

The letter A designates the track; B B', the 35 signal-posts, each having at the top a pivoted signal-arm c, at the bottom a lever d, and a rod e, connecting said arm and lever. Two of these posts constitute a block for each track of a double-track road. For a single-track 40 road four posts are necessary for each block—two on each side of the roadway.

In the present instance the system is shown as for a single-track road. In the case of a single-track road two wheel-treadles C are 45 used—one close alongside of each rail and directly opposite each other. These treadles are pivoted at one end f, and the other end rises and falls. The treadles are shown separately in Fig. 9. They are both alike in their 50 peculiar shape, but are placed in reversed position with respect to each other—that is, the

pivoted end f of one is opposite the free end of the other, as shown. From the pivoted end to the highest point g at the center each treadle has a gradual continuous slope g', 55 but from the free end toward the center is first a low horizontal part h and then an abrupt slope h' to the high center g. From this construction of treadle and reversed position of the two treadles it will be seen that one 60 treadle will be depressed before the other by a locomotive or train, depending on the direction of movement. A train approaching the two treadles will strike and depress first that one whose gradual continuous slope g' is toward the approaching train. The connections with the other treadle thereupon will instantly be disengaged or broken.

The free end of each wheel-treadle has pivoted to it a switch-arm i, which makes connection with the piston-rod i' of a power-cylinder D. The switch-arm i may be moved to disengage or break connection with the rod i'. The power-cylinder D has a piston and a spring j under it of power barely sufficient to 70 keep it normally elevated. When a car-wheel comes on the wheel-treadle C while the switch-arm i is in connection with the piston-rod i', the piston will be depressed and the air in the first power-cylinder D will be forced through 75 the pipe k' to the rear end of the first signal-operating cylinder E, which has a piston l, and rods l' d' connect with the lever d on the bottom of the signal-post. The movement of the piston l will cause the signal-arm c to be 80 moved.

The compressed air to supply the cylinders D E may come from any source or storage that may be provided. In the present instance we provide an air-pump F, to be 85 worked by a wheel-treadle G alongside of the track-rail. The air-pump (see Fig. 5) has an inlet-tube m in its head, a valve m' through its piston, and a spring n below the piston to quickly raise it. A pipe k leads 90 from the air-pump to the first power-cylinder D and has a check-valve n'.

The power-cylinder D has a blow-off or safety valve o to release the air if too much is forced in by the pump. A three-way valve 100 p is in the pipe k' to control and cut off the supply of air passing from the power-cylind-

der D to the signal-operating cylinder E. The valve-shank projects through the shell and on the exterior has a pinion p' , which gears with a rack q on the piston-rod i' .

- 5 When the piston is up, the valve will be open to the exhaust-port p^2 . When the said piston is down, the valve p will be turned to open the way for air to pass from cylinder D to cylinder E, which air will press on the piston l and thereby raise the signal-arm c on post B. The air-pipe k^2 continues past the first signal-operating cylinder E to second signal-operating cylinder E', located near the other post B'. This second cylinder has reversed 15 position with respect to the first cylinder—that is, the forward ends of the two cylinders are toward each other. The pipe k^2 between the two cylinders E E' has two automatic valves r , one of which is shown in section at 20 Fig. 10. Each of these valves is located at the connection with the pipe k^2 of the branch pipe s , leading therefrom to the forward end of the operating-cylinder.

When a train is moving in the direction of 25 the arrow and air is being forced by the first power-cylinder D, the flap r' of the automatic valve r at the first operating-cylinder E will swing up and close the branch pipe s and open the main pipe, and the air will pass on to the 30 valve r of the second operating-cylinder E', the flap of which will swing down and close the main pipe and open the branch pipe, whereby the air will enter the rear end of the first cylinder E and the front end of the second cylinder E', and thus the signal-arm c on the two posts B B' will be raised, showing that the 35 block is occupied. The air-pipe k^2 continues from the second operating-cylinder E' to the second power-cylinder D'. After the train 40 has passed post B' and air is being forced by the second power-cylinder D' the action of the flap-valves, as above described, is exactly reversed, and the result is that the signal-arms c in the posts B B' will both be lowered, 45 showing that the block is open or unoccupied.

The air devices and the mechanism on one side of the road for operating the signals on one track have been described, and it now remains to be stated that this being a single-track road a duplicate set of these devices and mechanisms is provided along the other side of the road, and that means are also provided for connecting the two sets, whereby when a train passes along the track only one 50 set of signals will be operated—to wit, that set which is on the right-hand side of the roadway considered in the direction that the train may be moving. It will be understood that the other set, which is on the opposite 55 side of the roadway, will be thrown out of connection or rendered inoperative for the time being.

As already stated, each wheel-treadle C has a pendent switch-arm i , which normally hangs 60 down and rests upon the piston-rod i' of a power-cylinder. Each power-cylinder has on its top end an angle-lever, (designated on one

cylinder by the letter u and on another by u' .) The horizontal arm of each angle-lever is connected with the piston-rod i' in such 70 manner as to be moved up and down thereby. Attached to the pendent arm of each angle-lever is a rod, which in one instance is designated t and in the other t' . This rod leads from the angle-lever on the power-cylinder at one 75 side of the track and connects with the pendent switch-arm i , which is above and coacts with the piston-rod i' of the power-cylinder at the other side of the track.

As shown in Figs. 5 and 8, the power-cylinder D on one side of the track is diagonally and not directly opposite the power-cylinder D' on the other side of the track, and the switch-arm i of the treadle on one side of the track is disengaged from its piston-rod by a 80 rod t , leading diagonally to an angle-lever u on the power-cylinder on the other side of the track, and another rod t' and angle-lever u' in like manner operate the other switch-arm. It will be seen these rods, angle-levers, 85 and switch-arms constitute the means for connecting the two sets and rendering one of them 90 inoperative.

The signal-operating cylinders E E' have two exhaust-ports v —one at each end—and a 95 slide-valve w opens and closes the ports. A rod w' connects the slide-valve with a lever x , which is moved by the piston-rod l' . By reference to Fig. 10 it will be seen that when compressed air enters one end of the operating-cylinder 100 E and moves the piston l therein such movement will, through the action of lever x and rod w' , shift the slide-valve w so as to close the exhaust-port at the end of the cylinder where air has just entered and to open the 105 exhaust-port at the opposite end to allow the air therein to escape. This mechanism has been described herein as working by the actuation of compressed air. It is obvious, however, that other fluids may be employed to 110 operate it—for instance, oil or water.

Having described our invention, we claim—

1. In a block-signal system for railways, the combination of the signal-posts B B', each provided with movable signals, two power-cylinders D D', two signal-operating cylinders E E', a pipe connecting the two power-cylinders and having branches leading to two 115 ends of each of the said operating-cylinders, an automatic valve r at the connection of the main pipe with each branch pipe, which leads to the forward end of each of the operating-cylinders, and a wheel-treadle C, to force the air from each power-cylinder.

2. In railroad-signals, the combination of a 120 post having a movable signal, an operating-cylinder E, provided with a piston, connections between the said piston and movable signal, an air-pipe having open connection with one end of the operating-cylinder and a 125 branch s , leading to the other end, and an automatic flap-valve r at the connection of said branch with the air-pipe.

3. In a railroad-signal, the combination,

- with a movable signal, of two power-cylinders D D', having pistons, a signal-operating cylinder E, having a piston, a pipe connecting the two power-cylinders and branches into both ends of the operating-cylinder, an automatic valve *r* at the connection of the main pipe with the branch leading into one end of the operating-cylinder, a three-way valve *p* in the main pipe near one power-cylinder, 10 and a gear-connection between said three-way valve and the rod of the piston in the power-cylinder.
4. In a railroad-signal, the combination of a power-cylinder D, a piston in said cylinder, 15 a spring to elevate the piston, a wheel-treadle pivoted alongside of the track-rail, and a switch-arm *i*, pendent from the wheel-treadle and adapted to make and break connection with the rod of said piston.
5. In a railroad-signal, the combination of a post having a movable signal, an operating-cylinder E, provided with a piston and having an exhaust-port at each end, connections between the said piston and movable signal, 20 an air-pipe having open communication with one end of the operating-cylinder and a branch *s* leading to the other end, an automatic flap-valve *r* at the connection of said branch with the air-pipe, and a slide-valve *w*, which is operated by the movement of the piston for opening and closing the exhaust-port. 30
6. In a block-signal system for a single-track railway, the combination of signal-posts, signal-operating cylinders, and power-cylinders on both sides of the roadway, two pivoted wheel-treadles C, one at each side and directly opposite each other, but placed in reversed position with respect to each other, a switch-arm *i*, pendent from each wheel-treadle 40 and movable to and from a piston-rod of one of the power-cylinders, and connections between the switch-arm on one side of the road and a lever operated by the power-piston rod on the other side of the road, and vice versa, 45 for making and breaking connection between the switch-arms and piston-rods.

In testimony whereof we affix our signatures in the presence of two witnesses.
